VALVE

Roy B. Bryant, Dallas, Tex.; Frank Leone Bryant,
executrix of the will of said Roy B. Bryant,
deceased

Application November 14, 1936, Serial No. 110,795

10 Claims. (Cl. 103—232)

This invention relates to new and useful improvements in valves.

One object of the invention is to provide an improved valve adapted to be connected in a well tubing for controlling the introduction of a lifting fluid into said tubing, whereby the well liquid is raised in said tubing.

An important object of the invention is to provide an improved flow valve which is actuated by the differential of pressure within the well tubing and well casing, there being positive means for holding the valve open to permit the admittance of lifting fluid into the tubing until such time as the tubing above said valve is entirely emptied of well liquid.

Another object of the invention is to provide an improved flow valve which is so constructed that a definite pressure differential between the pressures in the tubing and casing is required to open said valve to admit the lifting fluid into the tubing, whereby the presence of well liquid in the tubing above the valve, and the presence of sufficient lifting fluid in the tubing is assured before the valve is opened, thereby producing efficient operation, as well as conserving the lifting fluid.

A further object of the invention is to provide an improved flow valve which is so arranged that an excessive column of well liquid will not be built up in the well tubing above the valve, whereby the lifting medium is always sufficient to raise said liquid.

A further object of the invention is to provide an improved flow valve assembly which may be bodily removed from the well tubing, whereby mounting or dismounting thereof is facilitated; the entire structure being simple in construction, whereby manufacturing costs are reduced to a minimum.

40 A construction designed to carry out the invention will be hereinafter described, together with other features of the invention.

The invention will be more readily understood from a reading of the following specification and by reference to the accompanying drawing, in which an example of the invention is shown, and wherein:

Figure 1 is an elevation of a portion of a well tubing having a plurality of flow valves, constructed in accordance with the invention connected therein.

Figure 2 is a transverse, vertical, sectional view of the flow valve showing the ball in its lower seated position,

55 Figure 3 is a similar view, with the ball in an intermediate position,

Figure 4 is a similar view, with the ball in its upper seated position, and

Figure 5 is a horizontal, cross-sectional view, 60 taken on the line 5—5 of Figure 4.

In the drawing, the numeral 10 designates the usual well casing which has the well tubing 11 extending axially therethrough. The tubing and casing are, of course, of different diameters whereby an annular space is formed between the tubing and casing. In carrying out the invention, a plurality of flow valves 12 are connected in the well tubing 11, being spaced from each other throughout the length of the tubing string. Each valve includes a coupling collar 13 which is internally screw-threaded at each end, whereby said collar may be readily connected to the usual well tubing.

A valve housing 14 is formed at one side of the collar 13 and is preferably made integral therewith. The housing is elongate being substantially the same length as the collar 13, and the outer surface of the housing is rounded (Figure 5), while its lower end is bevelled at 14', whereby when the housing is lowered within the well casing with the tubing string 11, said housing will not hang or catch on the inside couplings of the well casing 10.

An axial bore 15 extends from a point near the lower end of the housing 14 to the extreme upper end thereof and the bore is preferably cylindrical. A flanged valve seat member 16 is disposed within the lower end of the bore 15 of the housing, and this member is provided with an axial bore 17 extending therethrough. When 30 the member 16 is within the bore 15 (Figures 2, 3 and 4), the lower end of the bore 17 of said member communicates with the upper end of angular ports 18 which are formed in the lower end of the housing 14. The opposite ends of the 35 ports 18 are open to the interior of the well casing, whereby a communication is established between the interior of the casing and the bore 17. A suitable packing ring 19 is interposed between the underside of the flanged member 16 40 and the bottom of the bore 15 to prevent leakage at this point.

The upper end of the bore of the member 16 is enlarged and is formed with an annular valve seat 20. The member 16 is externally screw-threaded to receive the lower end of an elongate sleeve 21 which is inserted within the bore 15 above said member. The outer diameter of the sleeve 21 is such that said sleeve has a tight sliding fit within the bore 15 of the housing. 45 The sleeve extends substantially throughout the length of the bore 15, its upper end terminating short of the upper end of said bore. The bore 22 of the sleeve 21 has a diameter slightly larger than the diameter of the enlarged portion of 50 the bore 17 in the member 16, as is clearly shown in Figures 2, 3 and 4. The bore 22 of the sleeve 21 is provided with a reduced portion 22', which portion is located nearer the lower end of said bore. The provision of the reduced portion 22' 55 60

forms an annular shoulder 23 at the upper end of such reduced portion, while an annular bevelled valve seat 24 is formed at the lower end of said portion. It is noted that the reduced portion 22' of the bore is located so that the seat 24 is spaced some distance above the annular seat 20 formed at the upper end of the member 16. A ball 25 is mounted in this space between the valve seats 20 and 24 and is adapted to engage one or the other of said seats, as will be hereinafter explained.

A piston 26 is mounted to slide within the upper end of the bore 22 of the sleeve 21 and normally rests upon the annular shoulder 23 formed at the upper end of the reduced portion 22' of the bore of said sleeve. The piston has a depending stem 27 which extends downwardly through the reduced portion 22' and has its lower end terminating in alignment with the valve seat 24, as is clearly shown in Figure 2. The piston is normally held on the shoulder 23 by a coiled spring 28 which is confined between the upper end of the piston and the underside of a flanged cap 29 which is threaded into the upper end of the bore 22 of the sleeve 21. A plug 30 is threaded into the upper end of the bore 15 of the housing 14 and has its underside engaging the cap 29 at the top of the sleeve 21, whereby said sleeve is firmly held within the bore 15. If desired, a suitable packing gasket 31 may be interposed between the plug 30 and the cap 29.

From the above, it will be seen that a communication is established between the bore 22 of the sleeve 21 and the annular space between the well tubing 11 and the casing 10, by means of the bore 17 of the member 16 and the angular ports 18 formed in the lower end of the body. Therefore, when the ball 25 is unseated, fluid may flow from the well casing through the port 18, bore 17 and into the bore 22 of the sleeve. For establishing a communication between the bore 22 of the sleeve and the interior of the well tubing 11, the sleeve 21 is provided with a radial port 32 which is located intermediate the reduced portion 22' of said bore (Figures 2 and 5). The port 32 has its outer end communicating with a radial opening 33 provided in the inner side of the valve housing 14 and collar 13. The opening 33 is open to the interior of the collar 13 and, therefore, to the interior of the well tubing, and thus, it will be seen that a communication is established through this opening and the port 32 between the well tubing 11 and the bore 22 of the sleeve. As has been pointed out, there is a communication between the bore and the interior of the well casing 10, and therefore, it follows that with the above arrangement a communication between the interior of the well tubing and the interior of the well casing is had. A vertical passage 34 connects the opening 33 with the upper end of the bore 22 of the sleeve 21, whereby the top of the piston 26 is subjected to the pressure of the fluid or liquid within the well tubing. It is noted that the lower end of the passage 34 terminates above the radial ports 32 in the sleeve and communicates with the upper end of the opening 33, as clearly shown in Figures 2, 3 and 4.

In operation, a plurality of the flow valves 12 are connected in the well tubing 11 at spaced points throughout the vertical length of the tubing string. Therefore, as the tubing is lowered into the well casing 10, the valves are low-

ered therewith. At this time there is no gas, or other lifting fluid within the well casing and, therefore, the ball valve 25 is resting on the seat 20 of the member 16, and the piston 26 is resting on the shoulder 23 being held so by the coiled spring 28. As the tubing 11 becomes filled with the well liquid, such liquid will rise above the valve housing 14 and the pressure of the fluid will be exerted against the upper end of the ball 25 through the opening 33, port 32 and bore 22 of the sleeve 21. At the same time the fluid will pass upwardly through the vertical passage 34 and will enter the bore 22 of the sleeve 21 to exert its pressure against the top of the piston 26 and aid said spring 28 in holding the piston in its lowermost position. At this time the pressure is equalized on both sides of the piston 26 and the ball 25 is acting as a check valve to prevent the well liquid within the tubing 11 from flowing into the well casing.

The gas, or other lifting fluid, is then introduced into the annular space between the well casing 10 and the tubing 11 and this gas pressure will act through the port 18 and bore 17 of the member 16 against the underside of the ball 25 of the uppermost valve. When the gas pressure has been built up sufficiently to overcome the pressure of the fluid exerted against the upper end of the ball, said ball will be unseated and moved upwardly to the position shown in Figure 3. At this time the ball can move only to this position because it will strike the lower end of the stem 27 of the piston 26 which is being held in its lowermost position by the coiled spring 28 and the pressure of the liquid within the well tubing. Therefore, the ball will be raised from the seat 20 to an intermediate position between the valve seat 20 and the upper valve seat 24, whereby the gas from the well casing may flow through the bore 22 of the sleeve 21, port 32 and opening 33 into the well tubing. The gas pressure, being greater than the pressure of the liquid within the well tubing can raise the ball 25 from its seat 20, but is insufficient to raise the piston 26 because the spring tension is added to the pressure of the well liquid within the tubing in holding said piston in its lowermost position. Therefore, the ball is held in an intermediate position between the valve seat by the stem and the gas or other lifting medium, flows around said ball and enters the well tubing.

Upon the initial admittance of the gas into the well tubing it will be obvious that said gas is acting against the fluid column in the well tubing above the valve and, therefore, the movement of the gas through the bore of the sleeve, through the port 32 and opening 33 is comparatively slow. However, as the column of fluid within the tubing becomes aerated the gas flowing through the bore 22 of the sleeve will increase its velocity. Also as the fluid column begins to move the pressure upon the piston 26 becomes gradually lessened. As the velocity of the gas increases and continues to increase, a back pressure is built up in the bore 22 of the sleeve 21 because of the restricted opening or port 32 in the wall of said sleeve. This back pressure will continue to build up because the velocity of gas will continue to increase as the fluid moves upwardly through the well tubing and when this pressure reaches a predetermined point it will overcome the tension of the coil spring 28 and raise the piston 26 within the

upper end of the bore 22 of the sleeve. When the piston 26 is moved upwardly by this gas pressure in the bore 22, the stem 27 depending from the lower end of the piston will be raised accordingly, whereby the ball 25 will be permitted to engage the upper annular seat 24 to close the bore 22. The upward movement of the ball 25 will, of course, be occasioned by the pressure of the lifting fluid within the well casing. The position of the valve at this time is clearly shown in Figure 4. As soon as the ball 25 engages the seat 24, it is obvious that the fluid from the well casing cannot enter the well tubing through this valve any longer. The valve is held in this position by the pressure of the fluid in the casing, and since this fluid cannot enter the tubing through the valve in its shut-off position, said fluid pressure will act upon the valve next thereto below to operate it in the same manner.

The valve will remain in its closed position so long as the fluid pressure within the casing 10 is greater than the pressure of the well liquid within the tubing plus the tension of the coiled spring 28. Thus, until such time as the well liquid again builds up in the well tubing 11 to a point where its pressure exerted against the top of the piston 26 and the top of the ball 25, plus the tension of the spring 28 which is sufficient to overcome the pressure of the lifting fluid within the well casing, the valve will remain closed or in the position shown in Figure 4. With this arrangement, the tension of the coiled spring is added to the pressure of the well liquid within the tubing to act against the pressure of the lifting fluid within the well casing. Obviously, by varying the tension of the coil spring 28 it is possible to accurately adjust the device so that a predetermined column of fluid will build up in the well tubing before the valve is opened.

This assures the proper amount of liquid being in the well tubing above the valve before said valve is open, and at the same time assures a sufficient pressure of lifting fluid in the well casing before the valve is opened. Therefore, a conservation of the lifting fluid is accomplished.

When the well liquid in the tubing has reached the point where its pressure, plus the pressure of the spring 28, is sufficient to overcome the pressure of the lifting fluid in the casing, the piston 26 will be moved downwardly to move the ball 25 from the upper seat 24. As soon as this occurs the gas or other lifting fluid is permitted to enter the bore 22 of the sleeve 21, pass around the ball 25 and into the well tubing, as has been explained. The gas continues to enter the well tubing until its velocity has reached the point sufficient to build up a back pressure beneath the piston 26, at which time said piston is raised to again permit the ball 25 to engage the seat 24. Therefore, during the operation of the valve, the ball 25 is alternately moved to engage and disengage the seat 24. It is noted that during the actual operation the ball 25 never engages the lowermost seat 20. The only time that the ball engages this seat is when there is no fluid pressure within the well casing at which time gravity permits the ball to engage this lower seat so as to act as a check to prevent any liquid within the well tubing from flowing into the well casing.

It is noted that there are few working parts to the device and it is very simple in construction. By removing the plug 30 from the upper end of the bore 15 of the valve housing 14, it is possible to remove the entire assembly. If it is only desired to remove the spring 28 to either re-

place the same or substitute a new one therefor, it is only necessary after removing the plug, to remove the flanged cap 29 and insert a new spring. The provision of the ball 25 assures a tight seal when said ball is seated and prevents any leakage of pressure thereby.

What I claim and desire to secure by Letters Patent is:

1. A flow valve including, a housing adapted to be connected in the well tubing within a well casing and having a bore communicating with the interior of said tubing and also communicating with the interior of the well casing, whereby communication between the tubing and casing is established through said bore, a valve in the bore 15 for controlling the flow therethrough and actuated by the differential in pressures within the tubing and casing, movable means movable independently of the valve having one side subjected to the pressure within the tubing and its 20 opposite side subjected to the pressure in the casing for holding the valve in an open position until the pressure within the casing has reached a predetermined point, and resilient means engaging the movable means on the side which is 25 subjected to the pressure in the tubing, whereby by the tension of said means is added to such tubing pressure in operating the movable means.

2. A flow valve including, a collar adapted to be connected in a tubing string, a housing having a bore carried by the collar, said bore communicating with the exterior of the housing and also communicating with the interior of the collar, a valve in the bore for controlling the flow therethrough and actuated by the differential in 30 pressure between the interior of the collar and the exterior of the housing, movable means within the bore having both sides exposed to the pressure within the collar when the valve is closed and having one side exposed to the pressure 40 within the interior of the collar and its opposite side exposed to the pressure exteriorly of the housing when the valve is open, whereby when the valve is open said movable means is actuated by the differential pressure for holding the valve 45 open until the exterior pressure reaches a predetermined point, and resilient means acting on said movable means for aiding the pressure within the collar to resist movement of said means by the exterior pressure.

3. A flow valve including, a housing adapted to be connected in the well tubing within a well casing and having a bore communicating with the interior of said tubing and also communicating with the interior of the well casing, whereby communication between the tubing and casing is established through said bore, a double valve seat within the bore, a valve adapted to engage said seats and actuated by the differential in pressure between the casing and the tubing, said valve engaging one seat and acting as a check when the pressure within the tubing is greater than the pressure in the casing, and movable means within the bore and also actuated by the pressure differential for holding the valve between its seats to permit flow of fluid from the casing to the tubing at a predetermined pressure differential and for permitting the valve to engage the other seat to close when the pressure in the casing reaches a predetermined point.

4. A flow valve including, a housing adapted to be connected in the well tubing within a well casing and having a bore communicating with the interior of said tubing and also communicating with the interior of the well casing, whereby communication between the tubing and casing

- is established through said bore, a double valve seat within the bore, a valve adapted to engage said seats and actuated by the differential in pressure between the casing and the tubing, said valve engaging one seat and acting as a check when the pressure within the tubing is greater than the pressure in the casing, and a movable piston within the bore and having one end subjected to the pressure in the tubing and its other end subjected to the pressure in the casing for engaging the valve to hold the same in a position between the valve seats to permit flow from the casing to the tubing when the pressure differential is at a predetermined point, said piston being actuated when the pressure in the casing reaches a predetermined point to permit the valve to engage the other seat to close the bore.
5. A flow valve including, a housing adapted to be connected in the well tubing within a well casing and having a bore communicating with the interior of said tubing and also communicating with the interior of the well casing, whereby communication between the tubing and casing is established through said bore, a double valve seat within the bore, a valve adapted to engage said seats and actuated by the differential in pressure between the casing and the tubing, said valve engaging one seat and acting as a check when the pressure within the tubing is greater than the pressure in the casing, and a movable piston within the bore and having one end subjected to the pressure in the tubing and its other end subjected to the pressure in the casing, a stem on the piston for engaging the valve to hold the same between its seats at a predetermined pressure differential, and resilient means exerting its pressure against the end of the piston subjected to the tubing pressure, whereby said means aids such pressure in the tubing in resisting movement of the piston by the pressure in the casing so that a predetermined pressure in the casing is necessary to move the piston to permit the valve to engage its other seat and close the opening.
6. A flow valve including, a housing adapted to be connected in the well tubing within a well casing and having a bore communicating with the interior of the well casing, whereby communication between the tubing and casing is established through the bore, a valve element within said bore for controlling the flow therethrough and actuated by the differential of the pressures within the casing and tubing, and a piston slidable in the bore and having means carried thereby for positively holding the valve element in an open position until the pressure in the bore reaches a predetermined point, said piston having the pressures thereacross equalized when the valve element is in a closed position and having opposite sides exposed to the pressures in the casing and tubing when the valve is open, whereby said piston is actuated by said pressure differential when the valve element is in its open position.
7. A flow valve including, a housing adapted to be connected in the well tubing within a well casing and having a bore communicating with the interior of the well casing, whereby communication between the tubing and casing is established through the bore, a valve element within said bore for controlling the flow fluid there-

through and actuated by the differential of the pressures within the casing and tubing, and a piston within the bore above the valve element movable independently of the valve element having one side exposed to the tubing pressure and its opposite side exposed to the casing pressure, whereby said piston is actuated by the differential in said pressures for positively holding the valve element in an open position until the pressure of the fluid reaches a predetermined point.

8. A flow valve including, a housing adapted to be connected in the well tubing within a well casing and having a bore communicating with the interior of the well casing, whereby communication between the tubing and casing is established through the bore, a valve element within said bore for controlling the flow fluid therethrough and actuated by the differential of the pressures within the casing and tubing, a piston within the bore above the valve element having both sides exposed to the tubing pressure when the valve element is open and having one side exposed to the tubing pressure and its opposite side exposed to the casing pressure when the valve element is open, whereby said piston is actuated by the differential in said pressures for positively holding the valve element in an open position until the pressure of the fluid reaches a predetermined point, and resilient means engaging the piston on the side subjected to the pressure in the tubing, whereby the force of said means is added to the tubing pressure in operating the piston.

9. A flow valve including, a housing adapted to be connected in the well tubing within a well casing and having a bore communicating with the interior of the well casing, whereby communication between the tubing and casing is established through the bore, a valve element within said bore for controlling the flow therethrough and actuated by the differential of the pressures within the casing and tubing, a piston slidable in the bore above the valve element movable independently of said element and actuated by the differential in said casing and tubing pressures, and a depending stem on said piston adapted to engage the element for holding the same in an open position until the pressure in the casing has reached a predetermined point.

10. A flow valve including, a housing adapted to be connected in the well tubing within a well casing and having a bore communicating with the interior of the well casing, whereby communication between the tubing and casing is established through the bore, a valve element within said bore for controlling the flow therethrough and actuated by the differential of the pressures within the casing and tubing, and a piston within the bore having pressure thereacross equalized when the valve is in a closed position and having opposite sides exposed to the tubing and casing pressures respectively when the valve is open, whereby when said valve element is in its open position, the piston is actuated by the differential in said pressure in the tubing and casing, said piston coacting with the valve element to control the inlet of a fluid to the tubing in accordance with the pressure in said tubing.
